UNITED STATES PATENT OFFICE.

EDWARD A. WALKER, OF PHILADELPHIA, PENNSYLVANIA.

PLANING-MACHINE.

SPECIFICATION forming part of Letters Patent No. 475,004, dated May 17, 1892.

Application filed April 18, 1891. Serial No. 389,422. (No model.)

To all whom it may concern:

Be it known that I, EDWARD A. WALKER, of the city and county of Philadelphia, State of Pennsylvania, have invented a certain new and useful Improvement in Planing-Machines, of which the following is a true and exact description, reference being had to the accompanying drawings, forming a part of this specification.

10 My present invention relates to the mechanisms which control the feed or tool and work presenting movements of planing-machines, and it is especially adapted for use with metal-planing machines, in which the tool is driven by being attached to a carriage that is situated upon, guided by, and moved to and fro along the bed of the machine while the work is held stationary beneath it.

20 The chief object of my said invention is to provide in the mechanism which automatically transmits feed motions to the tool-holding part of such a planing-machine's carriage an improved frictional clutch operative to 25 vibrate the main driving-shaft of such planer's feed mechanism in the manner of a rock-shaft, said shaft being further limited in the motions thus imparted to it to a definite angular throw by means of abutting devices 30 ancillary to the clutch aforesaid. Further objects are to contrive said improved clutch mechanism in such manner that it may be actuated in direct connection with the to-and-fro movements of the planer's carriage along 35 its bed, to associate the mechanism controlling the reciprocations of such a planer's carriage with mechanism secured to the bed of the planer and adapted to impart movement to the planer's feed mechanism upon the 40 reciprocation of the carriage aforesaid by a direct and simple gearing, and by this means to supplement and give mutual support to parts which would otherwise have to be considerably heavier, together with such further 45 objects as will be apparent from this specification taken as a whole.

The new and useful features of my said present invention will be found collected in the combinations set forth in the following 50 claims; and reference now being had to the accompanying drawings, forming part of this

specification, they will be found to illustrate my said invention as follows:

Figure 1 is a plan view of a planing-machine provided with my improved device in 55 its preferred form; Fig. 2, an end view of a fragment of the main portion of the machine shown in Fig. 1. Fig. 3 is a cross-sectional view on the line 1 2 of Fig. 1. Fig. 4 is a side elevation of a portion of the machine. Fig. 60 5 is a cross-sectional view upon the line 3 4 of Fig. 3. Fig. 6 is a cross-sectional view upon the line 5 6 of Fig. 3. Fig. 7 is a cross-sectional view upon a somewhat smaller scale of a modification of a fragment of the structure 65 illustrated in Fig. 3; and Fig. 8 is a cross-sectional view of a further modification of the structure shown in Fig. 3.

In general A is the bed of the planer, a a' 70 its guideways, and B a carriage having a suitably recessed foot B', whereby it is supported upon, guided by, and movable along the top of the bed aforesaid.

C is a screw, which, being journaled without end movement to the bed of the machine, 75 engages the carriage B by means of a nut or nuts, (not shown in the drawings,) and thereby upon its rotation in opposite directions imparts reciprocal movement to the carriage B along the bed aforesaid. To effect such rotation in the screw, the machine is in this instance adapted to be actuated by a straight and a cross belt passing over the fast pulley D and the loose pulleys D' and D'', which pulleys are in ordinary manner mounted upon 80 the protruding shank of the screw C aforesaid. The position of said belts in relation to the three pulleys aforesaid being determined by the position of the shifter-arms m and m', and which arms being journaled to 85 vibrate horizontally over said belt-pulleys, as is shown in Fig. 1, they are then controlled in their position by means of a shipper-slide n, viz: The shipper-slide n, passing between the pivotal supports of the said arms m' and m, being attached to and guided by the bracket Y', (secured to the rear of the bed A,) has formed upon its sides projections n' n'', which projections are adapted to bear upon the horns of crescent-shaped lugs m' m'', that are 90 fixed to and vibrate with the said arms m' m''. By this contrivance it will be readily under-

stood that when the shipper-slide n is moved endwise the belt-shifter arms aforesaid are concurrently and correspondingly vibrated. Now to determine a proper length of such 5 endwise movement, so as to pass the belts to and fro off the fast and loose pulleys and to do it with convenience to the machinist operating the planer I have in this instance shown a throw-rod W , which, being bolted near the 10 bracket Y' to the inner end of the shipper-slide n , thence extends over both the bed and carriage of the planer to the bracket Y , through which it passes in a suitable manner for endwise movement without rotation, as 15 denoted by its rectangular section in Fig. 2, and while the mechanism which I prefer to use for imparting endwise motion to this throw-rod W by itself forms no part of my present invention and has lately been described by 20 me in an application filed October 1, 1890, Serial No. 366,776, I will here state that it consists of forming on or rigidly securing to said throw-rod a toothed rack-work w' , the length of which is preferably slightly in excess of 25 the maximum range of the carriage B along the guideways of the bed, and whose position is such that its rack-work engages with the pinion U , rotatably mounted upon a journal, such as the main tool-holder feed-shaft K , 30 which is in its turn rotatably mounted upon the planer's carriage B . The said pinion U being rigidly attached to a sleeve S , which, enveloping the shaft K aforesaid, extends across the same in the preferred construction to a 35 position most convenient to the operator, is there provided with a hand-wheel S' , by means of which the operator can, as described in my aforesaid application, manually control the length of the carriage's to-and-fro strokes 40 independent of its ordinary automatic reversing devices which in this instance are illustrated by the T-shaped slot w , fashioned in the side of the throw-rod W , the adjustable flange-headed studs v^2 , stops $v v'$, and abutment-bolt V , which, as shown in Fig. 1, is attached to the top of the carriage B .

F is the tool-holder of the planer. G and H (see Fig. 4) are shafts connecting with said holder and by which a proper transverse and 50 vertical feed is effected. However, as the particular mechanism for moving the tool-holder forms no part of my present invention, I have not thought it necessary to illustrate it further than by thus identifying the shafts G and H in the drawings. The shaft G is driven from the shaft H by means of pinions g and h , secured, respectively, to the said shafts. The shaft H is actuated by the lever h^2 , which is journaled on the shaft and to which are pivoted pawls $h^8 h^9$, which engage in ratchets h' , that are secured to the shaft H . By this construction, which is also a familiar one, the shaft H is turned when the lever h^2 moves in one direction, while the pawls move freely 60 over the face of the ratchets without turning the shaft when the lever moves in the opposite direction, and contrariwise when the

pawls are reversed. A reciprocating movement is given to the lever h^2 by means of the connecting-rod I , the other end of which rod 70 is adjustably fastened in a slotted arm J , which is secured upon the end of the shaft K aforesaid, which shaft, being journaled without end motion to the brackets $b b'$, that are formed integrally with or rigidly secured to 75 the carriage B , extends across said carriage in a horizontal position and carries upon it not only the hand-wheel S' , sleeve S , and the shipper-rod intermeshing gear U aforesaid, but also in close proximity to said gear another pinion M . Each pinion, being mounted loosely upon the shaft K , is operative to actuate said shaft as follows, viz: On each side of the preferably flat side faces of the said pinion M , I place correspondingly-faced friction-plates L and L' , the said plates being attached to the said shaft K in such manner that while both turn with it one of them (the one marked L in the drawings) is fixed (see the through-bolt l^4 , Fig. 3) and the other of them (L' of 80 Figs. 1 and 3) made longitudinally movable along the shaft K ; and, for the purpose of steadyng it in this movement the movable plate L' is preferably provided with a sleeve l , which, having a suitable seat, engages the key k^4 , fixed to shaft K , and also bushes the journal b . Beyond the bushing l the shaft K is provided with a screw-thread k^2 , upon which I mount a nut k' , and between this nut and the back of the bushing l I locate a spiral 90 spring N , by means of which I conveniently contrive that the side faces of the pinion M shall be clamped with resilient pressure between the adjoining side faces of the fixed and movable clamps $L L'$. In order to impart rotary motion to the pinion M , I attach, as by bolting to the offsets $y y'$ of the support Y' and the bracket Y , respectively, the straight-toothed rack R , for it will be obvious that when the carriage B is reciprocated by the 100 screw C the pinion M , meshing with the rack R , will be rotated back and forth, and that under the clamping action of the plates $L L'$, urged by the spring N , the said plates will, by means of the bolt l^4 and key k^4 , be efficient to 115 impart corresponding rotary motion to the shaft K , which carries the slotted head J , that actuates the feed-shafts H and G through the medium of the linkage $I h^2$, &c. In order to limit the throw of the shaft K at each reciprocation of the carriage B to less than a full revolution, I equip the friction-clutch with a stop device preferably constituted as follows: To the movable disk L' , I secure, as shown in 120 Figs. 3 and 4, a pair of projecting stops, 125 having plain abutment-faces $l' l'$. To engage with these abutments I locate at a suitable range a relatively-fixed stop, such as the end-wise-adjustable bar O , which, being inserted in a suitable orifice in the bracket b , is conveniently clamped thereto by a binding-screw o^2 in such manner that its end o' may project 130 within the range of the clamp-stops aforesaid. In short, as the traveling carriage B is driven

back and forth along the bed A the rack R serves to rotate reciprocally the pinion M. Thereupon the frictional contact between the sides of said pinion and those of the clamps 5 L L' causes the said parts to act as a clutch, and thereby and at the beginning of each stroke of the carriage B aforesaid imparts rotary motion to the shaft K, which motion of said shaft, being interrupted by the stop mechanism aforesaid—viz., parts designated O I o'—is limited to the initial part only of each stroke forward or backward of the carriage, and a rocking motion of the desired sort is thus imparted at those moments to the slotted 15 arm J, which arm, being fixed, as above mentioned, to shaft K, thence through rod I, transmits motions as feed movements to the lever h² aforesaid.

In Fig. 1 I have shown a bracket k⁹ and the 20 step-screw k¹⁰, adapted to take the thrust of the shaft K endwise in its bearings in the brackets b b'. This enables me to make the bearing of the shaft K in the bracket b' without a neck or collars, which I deem an 25 advantageous construction. Referring to Fig. 3 it will also be seen that the gear U, as there illustrated, when viewed in section shows a chambered or overhanging form by which the fixed clamp L of the clutch is conveniently 30 and compactly housed. The gear U, being mounted upon the sleeve S, is fixed thereto by a set-screw s.

In Fig. 8 I have shown the stop l', which 35 limits the motion of the shaft K, secured directly to that shaft and not carried by the friction-plates, which serve to clamp said shaft with resilient pressure to the intermediate pinion M. In order to afford the stops when thus carried by the shaft a convenient 40 abutment, I have shown in Fig. 8 the adjustable bar O with its rear part retreated within range of said stop or stops.

In Fig. 7 the modification consists in mounting the pinion M upon a bushing M', through 45 which a keyway is fashioned. By this means the clamping-plates of the clutch, which here, being of a somewhat modified form, I designate as L¹⁰ L¹¹, are secured to the shaft K by a preferably continuous key Z, that is adapted to 50 pass through seats that are fashioned for it in both of them, the shaft K and the bushing M' aforesaid. This construction I prefer for the reason of its simplicity, coupled with the fact that the bushing may be made of anti- 55 friction metal, and so reduce the wear entailed by the constant rotation of the pinion M when the carriage is reciprocated. The key Z in this modification, instead of being continuous, may, as indicated by broken lines 60 adjoining the contact-faces of the clamps and pinion M, be interrupted and formed in three sections, should that be found desirable.

In conclusion, as the T-shaped slotting and considerable length of the throwrod W tends to 65 weaken it I preferably take advantage of the close association and parallel alignment with it of the clutch-rod R and combine said rod and

rack for mutual support. This is illustrated in Figs. 1 and 3, where the clips or lugs r, having an L-shaped section, are bolted to the 70 tops of the throw-rod W and by bearing upon the top and outer face of the rack R afford supports to the throw-rod without hindrance to its endwise movement. The rod thus supported also tends to stiffen the rack from being bent laterally. It will also be borne in mind that I limit my present invention, so far as the same refers to the clutch mechanism of the tool-feed, to one where the intermediate and driving member thereof is not 75 adapted to be relieved from the stress of its clamping members, the frictional contact being in this case contrived to be overcome upon the positive abutment of the stops and not relieved by the retraction of the resilient 80 clamps, as was described and claimed by me in my patent, No. 454,960, of June 30, 1891.

Having now described my invention, what I claim as new, and desire to secure by Letters Patent, is—

1. In a planer, the combination, with the tool-carrying carriage, of the feed-shaft K, a gear-wheel M, journaled thereon, friction-plates fixed radially to shaft K and arranged to clasp wheel M between them with resilient 95 pressure, a stop or stops connected with shaft K, another stop or stops attached to some relatively fixed part of the machine and arranged to engage the stop or stops aforesaid and arrest the motion of shaft K, but without 100 relaxing the pressure of the plates aforesaid upon wheel M, and a stationary rack R, directly engaged with the gear M, so as to rotate it as the carriage aforesaid moves over the bed of the planer, substantially as and for 105 the purpose described.

2. In a planing-machine having a fixed bed, as A, a movable tool-carrying carriage, as B, and mechanism for feeding the tool and reciprocating the carriage, as described, the 110 combination of a sliding shifter-bar W for controlling said reciprocating mechanism, a fixed rack R, the said shifter-bar and rack being suspended contiguously above said bed, as by brackets Y Y', and adapted to mutually 115 support each other, as by clips r, and a pinion, as M, operatively connected with said rack and operative to impart motion to said feed mechanism upon the reciprocation of said carriage, substantially as and for the 120 purposes hereinbefore described.

3. In a planing-machine having a fixed bed, as A, a movable tool-carrying carriage, as B, and mechanism for feeding the tool and reciprocating the carriage, as described, the 125 combination of a slide shifter-bar, as W, provided with rack-work of a length as described, a fixed rack R, the said shifter-bar and fixed rack being above said bed, a pinion M, rotatably journaled upon a main feed-motion drive-shaft K, said pinion being so located thereon as to mesh its teeth with the fixed rack R aforesaid, the said shaft K, a gear U, and hand-wheel S', rigidly fixed together, as 130

by sleeve S, and rotatably mounted upon said shaft K, the said gear U being adapted to mesh with the rack-work upon the shifter-bar W aforesaid, clamps radially fixed to shaft K, and means for applying said clamps as resilient friction-clutches to the gear M aforesaid, a stop device consisting of a member or members fixed to the shaft upon one hand and upon the other to some relatively-fixed part of the machine, the said device being operative to limit said shaft's rotative move-

ment to a limited degree, and means, as cross-head J, link I, rock-arm h^2 , pawl h^3 , and a ratchet h^4 , for transmitting the rocking movement of the shaft K to said feed mechanism 15 of the planer, substantially as and for the purpose specified.

EDWARD A. WALKER.
